UNITED STATES PATENT OFFICE

PAUL M. GAULT, OF ST. LOUIS, MISSOURI

SIGNALING SYSTEM

Application filed January 18, 1930, Serial No. 421,630. Renewed March 12, 1932.

The invention relates to a signaling system, and has particular reference to a track indicator for association with railroad yards employing a number of sidings which branch from a main or a plurality of main tracks.

In the maintenance of freight yards at the present time it is a common practice to employ an attendant whose chief duty it is to see that the incoming freight trains are properly switched and routed to the particular tracks to which they are destined. This may depend on several conditions of which the yard attendant only has knowledge, as for example, the nature of the freight, the particular wholesaler to whom the freight is consigned, and the various tracks which at the time may be vacant. It has therefore been necessary for the engineer of an incoming freight train to stop at the entrance to the yard and communicate with the yard attendant to ascertain the particular track to which his train is assigned.

The invention has for its primary object the provision of a novel mechanism which will serve as an indicator for incoming freight trains upon which signals can be flashed showing the particular tracks selected for the various trains.

Yet another object is to provide a device of simple construction which will be situated at the entrance to freight yards and serve as a means of information to the engineers of incoming trains, and thus obviate the delay in communicating with the yard attendant.

Another object is to provide an indicator for use in freight yards which can be operated by a yard attendant conveniently while at a distance from the device.

These and other objects are accomplished by means of the arrangement disclosed on the accompanying sheet of drawing, in which—

Figure 1 is a diagrammatic layout of a freight yard showing the system of tracks employed and the storage facilities or freight sheds associated therewith;

Figure 2 is a fragmentary front elevation of an indicator embodying features of the present invention; and

Figure 3 is a fragmentary side elevation of the same.

A diagrammatic layout of a typical freight yard is disclosed in the drawing wherein a set of tracks 10 are operated by a certain railroad, and tracks 12 are owned and operated by a subsidiary or competing road, which roads use a common freight yard and shed, as is often the case. However, tracks 10 and 12 may comprise a system of trackage owned and maintained by the same road. The tracks are united to form a main track formation by suitable switch means such as 16. Various sidings or lengths of track 18 form the yard, and on them the freight cars are run to be unloaded and, under some conditions, reloaded with different freight and consigned to other points. The tracks 18 all abut or terminate at a freight shed 20 so that the handling of the freight is materially facilitated.

It will be understood that by reason of the number of sidings 18 and the fact that each siding is of a length to accommodate a considerable number of cars, the freight yard and shed cover a large area of ground which necessarily makes the distance between any point in the freight shed and the entrance for the trains quite considerable. It has heretofore been the practice to equip the yards with a telephone line having one station in the vicinity of tracks 10 and 12 and the other station within the shed 20 at a point 22, for example, convenient to the yard attendant. It was then necessary for the engineer of an incoming train to telephone the yard attendant upon arrival and secure his instructions. The present invention contemplates a signaling system for association with yards of the above character which will be operated by the yard attendant and serve to flash instructions to the engineer.

This system takes the form of an indicator 24 supported upon any suitable means such as a post 26 which has in turn fastened thereto a chamber 28 with a hinge door 30 for access to the electrical connections and other necessary mechanism which may be housed therein. The indicator proper is supported from the chamber 28 by a post 32 and con-

sists of a box-like structure having provided on its forward face a plurality of signal devices 34. These devices comprise conventional parabolic reflectors 36, although not limited to this specific type, and a front lens 38 having formed therein or secured thereon numerals such as 40 shown in Figure 2. Visors 42 are provided to project over the upper half of the lens to increase the visibility of the signals when illuminated.

10 The necessary electrical connections are made to the terminals 44 of each signal which will then run to a suitable control board located at the point 22 convenient to the yard attendant. The board, not shown as it comprises no part of the invention, is provided with the necessary number of control means to correspond with the number of signals 34 provided on the indicator. In the operation of the device it is only necessary for the yard attendant to operate the control board which will illuminate the particular number desired upon the indicator. This is accomplished shortly prior to the time an incoming train is expected, and upon arrival the engineer is informed of the particular siding which his freight is to be located on. In the event that a train arrival were expected upon tracks 10 and 12 at practically the same time, the indicator has provided for this purpose two signals having letters formed thereon such as N and B as shown which serve to indicate the particular road for which the signal is meant.

25 The indicator is intended to be located at a point in the vicinity of the entrance to the yards where its signals will be visible to all incoming trains. It will be appreciated that the device is not necessarily limited to a yard of the type disclosed but may be employed in association with any type of sidings which are common not only in freight yards but also in railroad terminals where trains are made up and wherein for this purpose a main track and a plurality of branch or sidings are maintained.

I claim:

1. In a signal system, in combination with a main railroad track and a plurality of sidings branching therefrom, an indicator adapted to be located adjacent said main track and at a point in advance of said sidings, said indicator being provided with a plurality of signal means and each corresponding to a given siding, and an additional signal for indicating the train to which one of said first named signals is directed.
2. In a signal system, in combination with a main railroad track and a plurality of sidings branching therefrom, an indicator adapted to be located adjacent said main track and at a point in advance of said sidings, said indicator being provided with a plurality of signal means, each corresponding to a given siding, an additional signal for indicating the train to which one of said first named signals is directed, and manually controlled means for causing optionally any of said signals to become operative.
3. In a signal system, in combination with a main railroad track and a plurality of sidings branching therefrom, an indicator adapted to be located adjacent said main track and at a point in advance of said sidings, said indicator being provided with a plurality of signal means, each corresponding to a given siding, an additional signal for indicating the train to which one of said first named signals is directed, and manually controlled means for causing optionally any of said signals to become operative.
4. In a signal system, in combination with a main railroad track and a plurality of sidings branching therefrom, an indicator adapted to be located adjacent said main track and at a point in advance of said sidings, said indicator being provided with a plurality of signal means, each corresponding to a given siding, an additional signal for indicating the train to which one of said first named signals is directed, and means for causing optionally any of said signals to become operative, said means being operated independently of the conditions of the tracks.

Signed at St. Louis, Mo., this 14th day of January, 1930.

PAUL M. GAULT.
